(57) CLAIM

I claim the ornamental design for a lounge furniture, as shown and described.

DESCRIPTION

This application is related to my concurrently filed applications Ser. No. 29/362,284, Ser. No. 29/362,286, and Ser. No. 29/362,287, each of which is also entitled lounge furniture. FIG. 1 is a perspective view of a first embodiment of a lounge furniture showing my new design;

FIG. 2 is a front view thereof;

FIG. 3 is a rear view thereof;

FIG. 4 is a right side view of the lounge furniture of FIG. 1, the left side view being a mirror image thereof;

FIG. 5 is a top view thereof;

FIG. 6 is a bottom view thereof;

FIG. 7 is a perspective view of a second embodiment of a lounge furniture showing my new design with a headrest;

FIG. 8 is a front view thereof;

FIG. 9 is a rear view thereof;

FIG. 10 is a right side view of the lounge furniture of FIG. 7, the left side view being a mirror image thereof;

FIG. 11 is a top view thereof; and,

FIG. 12 is a bottom view thereof.
